UNITED STATES PATENT OFFICE.

JAMES HENLY FRIER, JR., OF WEBSTER GROVES, MISSOURI.

INDICATING ATTACHMENT FOR SPEEDOMETERS.

Application filed August 22, 1927. Serial No. 214,583.

This invention relates to improvements in indicating attachments for speedometers, and consists in the novel construction hereinafter disclosed.

6 An object of the invention is to provide a device that may be associated with the usual speedometer of an automobile, whereby indication is given to the operator of predetermined distances travelled by the motor vehicle 10 in order to enable the operator to make the necessary adjustments and supply of oil, etc., required for the operation of the vehicle.

Another object of the invention is to provide a device that is connected with the usual 15 speedometer of a motor vehicle, said device being adapted to display progressively a plurality of panels upon which may be displayed legends of selected character.

Additional advantages of the invention 20 will be readily apparent from the following detailed description taken in connection with the accompanying drawing in which

Fig. 1 is a fragmentary view of an instrument board of a motor vehicle showing the 25 relationship of the device with the speedometer.

Fig. 2 is a view partially in section further illustrating the manner in which the device is connected with the speedometer.

30 Fig. 3 is a detail view in vertical section through the speedometer showing the connection between the speedometer mechanism and the shaft of the indicating device.

Fig. 4 is a view of the strip upon which 35 the several legends are displayed.

Fig. 5 is a cross section substantially on the line 5—5 of Fig. 2.

In the embodiment of the invention illustrated in the drawing the speedometer 1 is 40 shown as mounted in an instrument board 2 of a motor vehicle in the usual manner. Cutting through the instrument board is a window opening in which is set a frame 3 providing an elongated display opening through 45 which the several panels of the legend strip of the device are displayed. The legend strip shown in Fig. 4 is divided into a plurality of panels 4, the dimensions of each separate panel corresponding substantially to the area of the opening within the frame 3. The

50 legend strip may be made of paper, celluloid, or any suitable material, upon which the legends may be imprinted. The legend strip is carried on the periphery of a drum 5, the 55 drum, in turn, being carried on a shaft 6

which is journaled in a frame 7 of the speedometer. The inner end of said shaft extends within the frame and the shaft lies adjacent to the numeral wheels of the speedometer. The shaft 6 is coupled with a selected one of 60 the numeral wheels of the speedometer and, in the embodiment shown, is connected with the one hundred-mile gear 8 by a pinion 9 which meshes with said gear. The drum 5 is attached to the outer end of the shaft 6 65 in any suitable manner and preferably in releasable association therewith so that it may be set and coordinated with the speedometer. The legend strip may be secured to the periphery of the drum in any suitable manner, 70 preferably by adhesive material, so that it will have a permanent set relationship with the drum. The entire drum is encased in a cylindrical housing 10 having an integral inner end wall and a removable cap 11 at its 75 opposite end. The removable cap makes it possible to gain access to the end of the shaft 6 and to the drum so that the drum may be adjusted upon the shaft.

Obviously, from the disclosure of the construction, it will be understood that, when the one hundred-mile speedometer wheel is actuated through the usual mechanism of the speedometer, the shaft 6 is rotated a single tooth distance of the pinion 9. The adjustment is such that this rotation of the shaft 6 85 brings into view in the sight opening the next adjacent panel of the legend sheet.

It is contemplated that in use the legend sheet shall include certain panels having utility data thereon, such as the distance at which the oil is to be changed, and the intermediate panels shall include advertising data. Thus, for instance, if the device is set to indicate that, at the end of a five hundred-mile run, 90 oil is to be changed, the fifth panel would include the utility data and the intermediate panels would include certain advertising data. At the end of each one hundred-mile run a new display would come into view in the sight 95 opening, acting as a constant reminder to the operator of the motor vehicle and, as the panels are displayed progressively, a number of different advertisements will be displayed upon each rotation of the drum. 100

I am aware that the invention may be modified in various particulars without departing from the nature and principle thereof. Therefore, I do not restrict myself to unessential details of construction, but what I 105

claim and desire to secure by Letters Patent is:—

A device of the character described comprising a frame, a gear wheel supported in said frame for intermittent rotation, a shaft extending into said frame, means for imparting intermittent rotary movements to said shaft by said gear wheel, a drum mounted on the outer end of said shaft for rotation there-
by and being removable therefrom and re-

placeable thereon in selected adjustments about the axis of said shaft, a housing enclosing said drum and having an integral inner end wall adjacent to said frame and an open outer end permitting removal and replacement of said drum upon said shaft, and a removable cap enclosing the outer end of said housing. 15
